SWINGABLE WAND SKILL GAME DEVICE

John W. Ryan, Los Angeles, Phyllis Frederick, Manhattan Beach, and Charles R. Zimmerman, Los Angeles, Calif., assignors to Mattel, Inc., a corporation of California

Filed Jan. 25, 1967, Ser. No. 5,560

Term of patent 14 years

(Cl. D34—5)

FIG. 1

FIG. 2

FIG. 3

FIG. 4

FIG. 5

FIGURE 1 is a side elevational view of a swingable wand skill game device showing our new design;

FIGURE 2 is a top plan view taken along line 2—2 of FIGURE 1;

FIGURE 3 is a bottom plan view taken along line 3—3 of FIGURE 1;

FIGURE 4 is an end elevational view taken from the left of FIGURE 1; and

FIGURE 5 is an end elevational view taken along line 5—5 of FIGURE 1.

We claim:

The ornamental design for a swingable wand skill game device, as shown.
